UNITED STATES PATENT OFFICE.

LEWIS E. LARSON, OF FARGO, NORTH DAKOTA, ASSIGNOR TO SURE EDGE STROPPER COMPANY, OF MINNEAPOLIS, MINNESOTA, A PARTNERSHIP CONSISTING OF A. E. SMITH, W. G. MANCHESTER, J. F. IRWIN, J. F. OWEN, HERBERT JOHNS, AND E. G. HANSON, ALL OF MINNEAPOLIS, MINNESOTA.

RAZOR-BLADE HOLDER.

Application filed March 28, 1921, Serial No. 456,294. Renewed January 7, 1924.

To all whom it may concern:

Be it known that I, LEWIS E. LARSON, a citizen of the United States, residing at Fargo, in the county of Cass and State of North Dakota, have invented a new and useful Improvement in Razor-Blade Holders, of which the following is a specification.

My invention relates to holders for safety blades used in stropping the same upon an ordinary razor strop and particularly to the type of razor blade holder which comprises a pair of clamping members pivotally positioned within a handle and has for its object to provide means for pivotally mounting said clamping members within the handle so that the same can readily be assembled.

Another object of the invention is to provide means whereby the clamping members may be normally held in spaced relation to permit the ready insertion of a safety razor blade between the same and to arrange these members within the handle or holder so that the same may be pivoted upon a portion of the handle which serves as a fulcrum and so that said clamping members may be easily removed.

Another object of the invention is to provide the member adapted to operate the clamping means with suitable stops whereby said member is held in either its operative or inoperative position.

In carrying out my objects I provide a pair of clamping members insertable within a slot in the handle or holder of the device. These members are provided with notches adapted to engage a number of projections formed within the opening in the handle to be pivoted thereon, said projections having notches adapted to receive flat springs positioned between the said clamping members to normally hold the same apart. In providing the stop mechanism for limiting the movement of the actuating member for said clamping members I provide a stop secured to the spindle operating said actuating member, which stop is movable within a recess and is adapted to engage the end walls of said recess when said spindle reaches its required position in the operation of said clamping means.

The full objects and advantages of my invention will appear in connection with

the detailed description thereof and are particularly pointed out in the claims. 55

In the drawings, illustrating the application of my invention in one form:—

Fig. 1 is a full sized side elevational view of my invention showing the use of the same. 60

Fig. 2 is an enlarged longitudinal sectional view of the parts shown in Figure 1 and similar thereto, with a portion of the device cut away and with the clamping members shown in engaging position. 65

Fig. 3 is a cross sectional view taken on line 3—3 of Figure 2 with the clamps shown open. 70

Fig. 4 is a cross sectional view taken on line 4—4 of Figure 2. 75

Fig. 5 is a sectional view taken on line 5—5 of Figure 2 with certain parts removed.

Fig. 6 is a cross sectional view similar to Figure 3 with the clamping members in 75 operable position.

Fig. 7 is a side elevational view of a portion of one of the clamping members of the device.

In Figure 1, I have shown my invention 80 in its entirety which comprises principally a tubular handle 10 of elliptical cross section which is knurled throughout its length at 16 to provide a suitable surface upon the same by means of which the same may be 85 readily grasped. At one end 12 of this handle the same is formed with a longitudinal slot or opening 13 extending along a portion of the same, in which opening are insertable two razor blade clamping members 90 14 and 15 as best shown in Figure 3. Adjacent the other end 17 of handle 10 the same is formed with a rotatable extension 18 thereof by means of which the said clamping members 14 and 15 may be rendered 95 effective or ineffective at will in a manner to be presently described.

The exact construction of the clamping members 14 and 15 and the mounting of the same within the end 12 of handle 10 is 100 best shown in Figures 2, 3, 5 and 7, at the extreme ends of the slot 13, as best shown in Figure 5, the metal of portion 12 of the handle 10 is turned inwardly at 19 and 20 to form two inwardly extending oppositely 105 facing flanges. These flanges are adapted

2 to fit into longitudinal slots or notches 21 formed in each end of the clamping members 14 and 15 near the center portions thereof, as best shown in Fig. 7. The 5 flanges 19 and 20 are spaced from each other at 22 a distance sufficient to permit of the insertion of either of the clamping members 14 or 15 between the same. After either of the members 14 or 15 has been 10 inserted within the spaces 22 the same may be slid over to its operating position whereupon the second member inserted within the space 22 and likewise slid over on its corresponding flange to its operable position. When the members 14 and 15 are in 15 place within the device said members assume the positions indicated in Figure 3, said members being held in place on said flanges in a manner to be presently described.

For holding members 14 and 15 in spaced relation to one another I provide two spring clips 23 each of which is provided with a circular head 24 and two upwardly extending arms 25 and 26. These spring clips are adapted to be inserted in recesses 27 and 28 formed in the flange members 20 and 19 in a manner clearly shown in Figure 3, so that the head 24 thereof falls below said flanges 19 and 20 and so that the arms 25 and 26 engage the inner portions of the clamping members 14 and 15 tending to spread the same apart above the flanges 19 and 20, thereby causing said clamping members to be oscillated upon the edges of the opening 13 which serves as fulcrums for the oscillation of said clamping members 14 and 15, bringing the lower portions of said clamping members within the portion 12 40 of handle 10 together and causing the outwardly exposed portion thereof to be spread apart as clearly indicated in Figure 3. By means of projections 29 and 30 formed on the flange members 19 and 20 between recesses 27 and 28 accidental displacement of the spring clips 23 is prevented. The same are further prevented from falling out of the device by means of the head 24 which engages the underside of the flange members 19 and 20 adjacent the recesses 27 and 45 28. When the arms 25 and 26 of said spring clips are forced together the head 24 is reduced in breath sufficiently to permit the insertion of the same into the device while 50 after said arms are again expanded said head simultaneously expands and becomes large enough so that the spring clip cannot be withdrawn through the recesses 27 and 28. With the spring clip 23 in operation 55 the clamping members 14 and 15 are held seated upon the flanges 19 and 20 which serve to hold the same in proper position within the opening 13 so that the entire edges of said opening engage the sides of said members 14 and 15 serving as fulcrums

for the oscillation thereof as previously specified.

The device for operating the clamp members 14 and 15 comprises a spindle 11 which extends throughout the entire length of the handle 10 and is journaled in ends 31 and 32 thereof. This spindle is normally circular in cross section but has a cam portion at 33 positioned between the lower ends of the clamping members 14 and 15 which is elliptical in cross section and is adapted to spread the lower portions of clamping members 14 and 15 apart as indicated in Figure 6 when said spindle is rotated. At the extreme end of spindle 11 is attached the head 18 previously referred to which conforms in shape to the end 17 of handle 10 so that when said head is positioned as shown in Figure 1 the handle and head have a continuous appearance. When the holder is in operable position and the elliptical cam 22 positioned as indicated in Figure 6 the head 18 assumes the position indicated in Figure 1. It can be readily comprehended that when a safety razor blade is inserted between clamping members 14 and 15 as indicated in Figures 1 or 6, and the head 18 rotated to cause the cam member 33 to operate members 14 and 15 that the same oscillate upon the edges of slot 13 as fulcrum drawing the broad ends of said members together to securely clamp the safety razor blade as distinctly shown in Figure 6. In this manner the blade is firmly held while the same may be stropped upon an ordinary razor strop in a manner identical with the stropping of the ordinary form of razor.

For terminating the movement of head 18 relative to the handle 10, I provide a stop 34 which is formed on the end of spindle 11 adjacent its attachment to the head 18. As before stated, spindle 11 is journaled in an opening 35 formed in the extreme end 31 of handle 10. The stop 34 is operable in an enlargement 36 of the opening 35 and is adapted to engage side walls 37 and 38 of said opening when said head 18 reaches positions shown in Figures 1 and 2. Inasmuch as the periphery of opening 36 is concentric with that of opening 35 and inasmuch as the circular portion of spindle 11 engages opening 35 and the end of the stop 34 engages the circular opening 36 the said spindle is hence suitably journaled in the end 31 of handle 10, so that the same may be properly rotated to operate upon the clamping members 14 and 15.

Through the opening 35 enlarged as indicated at 36, the entire spindle including the elliptical cam member 33 may be removed from the device. For holding this in place I thread the extreme end 125 of the same at 39 and provide a nut 40 which is adapted to be screwed upon the 130

end of the same. After the device is in place nut 40 is screwed upon the threaded end of spindle 11 and the entire device is firmly held in place.

5 The advantages of my invention are manifest. The device is extremely simple in construction and operation and the clamping members adapted to grip the safety razor blade are very effective, thus making the 10 device highly practical. My improved holder may be used upon any of the forms of safety razor blades so as to hold the same in proper position for efficient stropping. When a double edged blade is used the same 15 may be readily reversed within the holder without damaging the edge which has already been stropped. The device is extremely neat and attractive in appearance and can be economically constructed, the parts being 20 easily constructed in great numbers and readily assembled within the holder.

In accordance with the patent statutes I have described the principles of operation of my invention, together with the apparatus which I now consider to represent the 25 best embodiment thereof, but I desire to have it understood that the construction shown is only illustrative and that the invention can be carried out by other means 30 and applied to uses other than those above set forth within the scope of the following claims.

I claim:—

1. A razor blade holder comprising a 35 handle having a slot along the same, a pair of clamping members positioned partly within the handle and extending through said slot, notches formed in said handle near the ends of the slot thereof, and means 40 co-operating with said notches for holding the clamping members pivotally attached to the handle.

2. A razor blade holder comprising a 45 handle, a pair of clamping members positioned within the handle, said members being formed with notches and a pair of oppositely positioned members adapted to engage said clamping members within their notches to pivotally hold the same within the handle.

3. A razor blade holder comprising a 50 handle, a pair of clamping members positioned within the handle, said members being formed with notches and a pair of 55 oppositely positioned flanges adapted to engage said clamping members within their notches to pivotally hold the same within the handle.

4. A razor blade holder comprising a handle, a pair of clamping members positioned within the handle, and resilient means positioned between said clamping members for holding said clamping members in normally spaced relation. 60

5. A razor blade holder comprising a 65 handle, a pair of clamping members positioned within the handle and a pair of spring clips, positioned between said clamping members, having oppositely positioned arms adapted to engage said clamping 70 members.

6. A razor blade holder comprising a handle, a pair of clamping members positioned within said handle, having notches therein, a pair of oppositely facing flanges secured 75 to said handle and extending through said notches for pivotally holding said clamping members within the handle, recesses formed within said flanges between the oppositely facing portions thereof and a spring clip 80 adapted to be positioned within said recesses between the members having portions engaging said clamping members to hold the same in normally spaced relation.

7. A razor blade holder comprising a 85 handle, means for securing a razor blade to the handle, a member for operating said securing means and means for terminating the movement of said member when the same reaches either its extreme operable or 90 inoperable position.

8. A razor blade holder comprising a 95 handle, means for securing a razor blade to the handle, a rotatable member for operating said securing means, a stop formed on said rotatable member, limiting means formed on said handle adapted to engage said stop for terminating rotation thereof.

9. A razor blade holder comprising a 100 handle, a head rotatably mounted in said handle, a spindle secured to said head, said spindle passing through an opening in the end of said handle, a projection formed on said spindle adjacent said head and an enlarged opening having a wall concentric with said first named opening on which said projection is adapted to rotate and end walls formed on said enlarged opening adapted to engage the sides of said stops 105 for terminating the movement of said head relative to the handle. 110

In testimony whereof I affix my signature.

LEWIS E. LARSON.
